Attorney

UNITED STATES PATENT OFFICE.

ROY RANKIN MYERS, OF CHICAGO, ILLINOIS.

DEVICE FOR OILING HANDSAWS.

1,314,420.

Specification of Letters Patent. Patented Aug. 26, 1919.

Application filed November 27, 1918. Serial No. 264,363.

To all whom it may concern:

Be it known that I, ROY RANKIN MYERS, a citizen of the United States, residing at Chicago, in the county of Cook and State 5 of Illinois, have invented certain new and useful Improvements in Devices for Oiling Handsaws, of which the following is a specification.

The present invention has reference generally to improvements in that class of inventions known as lubricators and more particularly relates to a device for oiling hand saws.

It is the primary aim and object of this 15 invention to provide a device of the above mentioned character designed for attachment to a wall or other support and also designed to accommodate lubricating pads positioned on opposite sides of the blade of 20 a hand saw when the latter is arranged in a supported position in the device.

More particularly the present invention 25 contemplates the provision of a device of the above mentioned character wherein a pair of complementary slotted plates are employed and shaped so that when arranged in superposed relation a chamber is formed therebetween for accommodating the lubricating pads, the adjacent edges of which 30 pads are arranged in close relation with each other and in alinement with the slots through the plates so that when the blade of the saw is moved through the slots the pads will contact with the opposite sides of the 35 saw blade for the lubrication of the saw while the saw is capable of being effectively supported by the plates when not in use.

Among the other aims and objects of this 40 invention may be recited the provision of a device of the above mentioned character wherein the number of parts are comparatively few, the construction simple, the cost of production low and the efficiency high.

Other objects, as well as the nature, characteristic features and scope of this invention 45 will be more readily apparent from the following description taken in connection with the accompanying drawings, and pointed out in the claims, forming a part of this 50 specification.

The invention is clearly illustrated in the accompanying drawings, in which:

Figure 1 is a perspective view of the device,

Fig. 2 is a transverse sectional view taken 55 through the device showing the saw in a supported position therein,

Fig. 3 is a fragmentary top plan detail 60 of the lower plate, and

Fig. 4 is a transverse sectional detail with 65 the saw removed.

Similar characters of reference are employed in all of the above described views 70 to indicate corresponding parts.

Referring now, more particularly, to the 75 accompanying drawings, there is provided a pair of complementary plates 1 and 2 arranged in superposed contacting relation 80 with respect to each other and having their adjacent faces pressed away from each other 85 to provide longitudinally extending opposed recesses 3 which when the plates are arranged together form a chamber and in addition 90 the recessed portions of the plates are formed with longitudinal slots 4 which are 95 positioned medially of the sides thereof and terminate short of the ends of the recessed portions, and aline with each other when the plates are positioned in superposed relation, as is apparent. The slot 4 in the upper 100 plate 2 is restricted near one end to facilitate the insertion of the saw blade, hereinafter described, between the lubricating pads hereinafter described. Integral ears 5 extend longitudinally from the respective ends 105 of the plates 1 and 2 and are designed to register with each other when the plates are arranged together.

In order to provide the improved lubricating means, lubricating pads 6 such as 110 strips of felt which are adapted to be saturated with oil, are arranged longitudinally in the chamber and are positioned so that the adjacent side edges thereof are arranged in close relation and these closely arranged 115 edges register with the slots 4. When accommodated in the chamber, the opposite side edges of the pads or strips are arranged in close relation with the adjacent side walls of the recessed portions 3 of the 120 plate, the arrangement being clearly indicated in Fig. 4.

In removably holding the plates in the relation described, suitable fastening means such as nut and bolt arrangements 7 are 125 associated with the registering ears 5 for the clamping of the plates together.

Supporting brackets generally designated

8 extend laterally from one side of one of the plates, preferably the lower plate 1, while the vertically disposed attaching portions 9 are adapted to be secured to a wall or other 5 main support 10 as by detachable fasteners 11 so as to in consequence maintain the plates in a laterally disposed position with respect to the wall.

In use, the blade 12 of the saw 13 is adapted 10 to be passed through the alining slots 4 in the plate and between the closely spaced and adjacent edges of the lubricating pads 6 so that when the saw is slid up and down through the slots, the pads being arranged 15 in yielding engagement with the opposite sides of the blade 12 thereof will effectively lubricate the blade. When the saw is not in use, the device serves as a support therefor, the blade 12 being positioned through 20 the slot with the adjacent edge of the handle 14 resting on the upper surface of the plate 2, the arrangement being clearly indicated in Fig. 2. By the employment of this device, it is apparent that the saw will always 25 be kept in a conveniently supported position and will always be oiled when it is desired to use the same.

It is believed in view of the foregoing description that a further detailed description 30 of the operation of the invention is entirely unnecessary. Likewise, it is believed that the advantages of the invention will be readily apparent.

Still further embodiments of the invention 35 than those herein especially defined may be resorted to as conditions or preference may dictate, as may be in keeping with the here-to appended claims.

Having thus fully described the invention,

what is claimed as new and desired to be 40 secured by Letters Patent, is:

1. A device of the character described including a pair of superposed complementary plates having their adjacent faces formed with opposed alining recesses to form a 45 chamber and having their recessed portions provided with longitudinally extending registering slots, lubricating pads arranged in the chamber and having their adjacent edges positioned in closely spaced relation and in 50 registration with the slots, the slot in the upper plate being restricted near one end to facilitate the insertion of a saw blade between the pads, means for removably clamping the plates together, and means arranged laterally of the plates for attaching and supporting the plates.

2. A device of the character described comprising a pair of superposed complementary plates having their adjacent faces formed 60 with opposed longitudinally extending and registering recesses providing a chamber and having their recessed portions provided with registering longitudinal slots positioned medially of the sides of the recessed portions 65 and terminating short of the ends thereof, ears projecting from the ends of the plates and registerable with each other, lubricating pads arranged in the chamber and having their adjacent edges positioned in closely 70 spaced relation and in registration with the slots, means engageable with the ears for removably clamping the plates together, and supporting and attaching brackets extending from one of the plates.

In testimony whereof, I affix my signature hereto.

ROY RANKIN MYERS.
